US00D809923S

(12) **United States Design Patent** (10) **Patent No.:** **US D809,923 S**
(45) **Date of Patent:** **** Feb. 13, 2018**

(54) **BOTTLE**

(71) Applicant: **CORNERSTONE CM, INC.**, Poland, OH (US)

(72) Inventors: **Michael G. Marantis**, Poland, OH (US); **Richard A. Ponton**, New Milford, CT (US); **Joshua W. Hubbard**, New Milford, CT (US); **Jonathan P. Richards**, Derby, CT (US)

(73) Assignee: **CORNERSTONE CM, INC.**, Poland, OH (US)

(**) Term: **15 Years**

(21) Appl. No.: **29/564,387**

(22) Filed: **May 12, 2016**

Related U.S. Application Data

(63) Continuation of application No. 29/509,033, filed on Nov. 13, 2014, now Pat. No. Des. 764,920.

(57) **CLAIM**

The ornamental design for a bottle, as shown and described.

DESCRIPTION

FIG. 1 is a top front perspective view of a bottle showing our new design;

FIG. 2 is front view of the bottle illustrated in FIG. 1;

FIG. 3 is a rear view of the bottle illustrated in FIG. 1;

FIG. 4 is a left side view of the bottle illustrated in FIG. 1;

FIG. 5 is a right side view of the bottle illustrated in FIG. 1;

FIG. 6 is a top view of the bottle illustrated in FIG. 1; and,

FIG. 7 is a bottom view of the bottle illustrated in FIG. 1.

The broken lines in the drawings illustrate the portions of the bottle that form no part of the claimed design.

The dash-dot-dash broken lines in the drawings depict the boundaries of the claimed design.

1 Claim, 4 Drawing Sheets
